(57) **CLAIM**

We claim the ornamental design for the food chopper blade tray, as shown and described.

DESCRIPTION

FIG. 1 is a top perspective view of the food chopper blade tray, showing my new design;

FIG. 2 is a top view of the food chopper blade tray;

FIG. 3 is a front view of the food chopper blade tray, the back view being a mirror image;

FIG. 4 is a right side view of the food chopper blade tray; and, FIG. 5 is a left side view of the food chopper blade tray.

The bottom view is unornamented and forms no part of the claimed invention. An illustrative blade arrangement is shown in dashed lines and forms no part of the claimed invention.
